UNITED STATES PATENT OFFICE.

WILBER REUBEN HITCHCOCK, OF CORNWALL, ONTARIO, CANADA.

DRILL ATTACHMENT.

No. 866,361.

Specification of Letters Patent.

Patented Sept. 17, 1907.

Application filed March 18, 1907. Serial No. 362,938.

To all whom it may concern:

Be it known that I, WILBER REUBEN HITCHCOCK, a citizen of the United States of America, residing at Cornwall, county of Stormont, in the Province of Ontario, Canada, have invented certain new and useful Improvements in Drill Attachments; and I do hereby declare that the following is a full, clear, and exact description of the invention, such as will enable others skilled in the art to which it appertains to make and

use the same.

My invention relates to drills; the object of my invention is to provide means for attaching a bit to the shank so that there is no danger of detachment in the operation of drilling; a further object is to provide means for quickly attaching a bit; a further object is to provide a construction which will permit the shaft being constructed of a softer or cheaper material than the bit, so that a supply of different sizes of bits may be carried in a small space, and will necessitate carrying only one shank; and, my invention consists of the construction, combination and arrangement of parts, as herein illustrated, described and claimed.

In the accompanying drawings, forming part of this application, I have illustrated one form of embodiment of my invention, in which drawings similar reference characters designate corresponding parts, and in which:

Figure 1 is a plan view; Fig. 2 is a plan view showing the locking sleeve removed from the screw-threaded portion of the shank; Fig. 3 is a side elevation showing the sleeves in section and in a position to permit the removal of the bit; and, Fig. 4 is a plan view of the shank showing the sleeves in section and showing the application of a rose bit.

Referring to the drawings, 1 designates a shank, having the dovetailed slot 2 in one end, adapted to receive the wedge-shaped shoulder 3 of the bit, which may be of any ordinary form of construction.

A friction sleeve 4 is disposed on the shank 1, and is provided with an enlarged bore 5 at its inner end adapted to pass over the screw-thread 6 formed on the exterior surface of the shank 1. By having the bore 5 enlarged, a shoulder 7 is left on the inside of the sleeve 4, which is adapted to abut against the screw-threads 6 to limit the movement of the sleeve 4 upward on the shank 1, and in forming the slot 2 in the shank, the slotted end is swung outward slightly, so as to limit the movement of the sleeve downward, so that the sleeve 4 is permanently retained on the shank 1.

With the sleeve 4 in the position shown in Figs. 1, 2 and 4, the wedge-shaped portion 3 of the bit is maintained in the slot 2, so that it cannot be removed, while the interiorly screw-threaded sleeve 8, in engagement

with the screw-thread 6, firmly locks the sleeve against movement.

55

In the form shown in Fig. 4, the sleeve 4 is provided with interior screw-threads 9, by means of which the lower end of the sleeve is firmly locked against the shoulder 10 formed on the upper side of the bit. The sleeves 4 and 8 may be provided with recesses 11, 60 adapted to receive a spanner, by means of which the sleeves may be tightened up on the screw-threads 6.

By the construction described, in boring a deep hole there is no danger of the sleeve 4 becoming displaced by striking against the walls of the hole as it is bored, which 65 has been a fault with forms of drills of this character heretofore used.

Having thus fully described my invention, what I claim as new, and desire to secure by Letters Patent, is:—

70

1. In a coupling device for drill bits, a shank provided with a dove-tailed slot, and a kerf extending therefrom into the body of said shank, a bit, a wedge-shaped coupling member formed integrally therewith and adapted for insertion into and removal from the aforesaid slot, and a 75 sleeve slidably mounted upon the aforesaid shank, and adapted to overlie the slot and coupling member therein to retain the same against removal.

2. In a coupling device for drill bits, a shank provided with a dove-tailed slot, and a kerf extending therefrom into the body of said shank, a bit, a wedge-shaped coupling member formed integrally therewith and adapted for insertion into and removal from said slot, shoulders on said bit, a sleeve slidably mounted on the aforesaid shank, said sleeve being adapted to overlie and lock in place the aforesaid coupling member, the lower edge of said sleeve being adapted to engage with the aforesaid shoulder on the aforesaid bit.

80

3. In a coupling device for drill bits, a shank having a screw-threaded portion, a removable bit adapted to be held in said shank, a counterbored locking sleeve slidably mounted on said shank, the counter-bore of said sleeve being adapted to partially inclose the aforesaid threaded portion, and means for locking said sleeve in operative position.

85

4. In a coupling device for drill bits, a shank, having a dove-tailed slot in the end thereof, and a kerf leading from said slot into the said shank, a bit, a wedge-shaped coupling member formed integrally therewith, retaining shoulders on said bit, a locking sleeve slidably mounted on said shaft, said sleeve adapted to overlie said slot and coupling member to retain the same in coupled relation, the lower end of said sleeve being adapted to abut against and rest upon the aforesaid shoulders, and a nut adapted to engage the aforesaid screw-threads and bear against the upper end of the said sleeve to hold the same against upward movement.

90

In witness whereof I have hereunto set my hand in the presence of two witnesses.

WILBER REUBEN HITCHCOCK.
